CLAIM

The ornamental design for a book light, as shown and described.

DESCRIPTION

FIG. 1 is a front, top perspective view of a book light, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view of the book light, shown in an alternate position; and,

FIG. 10 is another perspective view of the book light, shown in an alternate position.

The broken lines in the figures illustrate portions of the book light that form no part of the claimed design.
